UNITED STATES PATENT OFFICE.

EVARISTE GEERAERD, OF PRESTWICH, ENGLAND, ASSIGNOR TO GEORGE J. STANFIELD,
OF MANCHESTER, ENGLAND.

ELECTROLYTIC CELL FOR PRODUCTION OF OXYGEN AND HYDROGEN.

1,308,704.

Specification of Letters Patent.

Patented July 1, 1919.

Application filed May 17, 1917. Serial No. 169,363.

To all whom it may concern:

Be it known that I, EVARISTE GEERAERD, a subject of the King of Belgium, and resident of 8 Harrogate avenue, Prestwich, in the county of Lancaster, England, have invented new and useful Improvements in Electrolytic Cells for Production of Oxygen and Hydrogen, of which the following is a specification.

10 This invention relates to an improvement in electrolytic cells, wherein the liberated gases are kept separate and delivered from the cells through separate outlets.

The invention broadly consists in providing each electrode of the cell with a series of vanes, arranged in superimposed spaced relation and at such inclination to the electrode as to deflect the gas liberated at such electrode and direct the flow of such gas upward and toward the electrode at which it was liberated.

In the accompanying drawings:—

Figure 1 is a sectional view, partly broken away, showing two cells of the improved 25 type connected together.

Fig. 2 is an elevation of one half of one cell, seen from the inner side to show the relative arrangement of the vane.

Fig. 3 is a broken perspective of one half 30 of one cell, illustrating particularly the spacing of the vanes and the gas channels formed in the electrode.

In accordance with the present invention, each cell is made up of two substantially 35 identical half-sections, as 1 and 2. Each half section is, of course, of the appropriate metal for the gas liberation desired, and presents a plate portion 3, forming the electrode proper, with inturned edge portions

40 4. The inner edges of the edge portions 4 have outstanding flanges 5. When the halves of a cell are assembled to complete a cell, the flanges 5 are arranged in juxtaposition, and connected together by bolts 45 6, an insulating strip 7 being arranged between the flanges 5, as shown. The strip 7, throughout the upper portion of the cell, extends below the edge portion 4, forming what may be termed a gas screen 8.

50 The upper portion of each half of a cell is formed at spaced points with transverse conduits or pipe like sections 9 and 10, projecting inwardly from the edge portion 5.

The pipe like sections 9 and 10 of the separate halves of a cell, register respectively

when the halves are assembled to thus form independent gas conduits extending transverse the cell. With each side of a cell forming an electrode, as described, the gas conduit to receive the gas liberated at that 60 electrode is formed adjacent the upper end of the electrode with an opening or slot to admit the gas. Thus the conduit 9 will be slotted at 11 to receive the gas from one electrode, while the conduit 10 will be 65 slotted at 12 to receive gas from the other electrode.

A series of vanes 13 are arranged transverse each half of each cell, being disposed in spaced parallel relation, and inclined 70 downwardly and from the particular electrode. The vanes are of non-conducting material, as glass, or the like, and are held in proper relative positions by spacing blocks 14, also of non-conducting material, as 75 wood, or the like. The blocks, and also the ends of the vanes 13 rest in rear of edge strips 15, projecting inwardly from the vertical edge portions 4 of each half cell, as clearly shown in Fig. 3.

The surfaces of each electrode immediately in rear of the vanes 13 are formed with a series of vertically arranged channels 16, preferably quite fine or small in cross section.

80 These channels lead to the upper end of the cell, and form a passage for the gas liberated at the particular electrode.

The vanes are less in width than half the interior of the cell, leaving a clear vertical 90 passage between proximate ends of the vanes of a complete cell, as will be clear from Fig. 1.

The gas liberated at each electrode will, through the natural movement of the electrolyte from one electrode toward the other, tend to move toward the vertical center of the cell. If not counteracted this action would result in a mingling of the gases. The downwardly inclined vanes, however, 100 intercept this movement, and direct the gas upwardly and toward the electrode at which it was liberated, so that finally the gas travels up the channels 16, into its particular conduit, from which it may be directed 105 to a proper storage reservoir.

The upward travel of the gases, each on the electrode at which it was liberated, also tends to create a circulation of the electrolyte from the vertical center of the cell, and 110

this aids in preventing a mixing of the gases.

The electrodes are of course in circuit with conductors 17 and 18, and the cell is 5 preferably provided with a pipe, as 19, through which the electrolyte may be supplied to the cell.

Having thus described the invention, what is claimed is:—

- 10 1. An electrolytic cell having side walls forming electrodes, means for insulating said walls from each other, a series of vanes supported in spaced parallel relation transverse each side wall and inclining down-
wardly and inwardly therefrom, the side walls being formed with vertical channels in rear of and communicating with the spaces between the vanes, and independent gas conduits at the upper end of the cell in com-
munication, respectively, with the vertical channels of the side walls, whereby the gas liberated at each electrode is directed into its respective gas conduit.
- 15 2. An electrolytic cell having side walls

forming electrodes, means for insulating 25 said walls from each other, a series of vanes arranged transverse each side wall, spacing blocks arranged between the end portions of the vanes to maintain the vanes in spaced parallel relation and inclined downwardly 30 and inwardly with respect to the side wall, means to hold the blocks and the ends of the vanes in position, the side walls being formed with vertical channels in rear of and communicating with the spaces between 35 the vanes and independent gas conduits at the upper end of the cell in communication, respectively, with the vertical channels of the side walls, whereby the gas liberated at each electrode is directed into its respective 40 gas conduit.

In testimony, that I claim the foregoing as my invention, I have signed my name, this 1st day May 1917.

EVARISTE GEERAERD.
